United States Patent Office

Des. 196,627
Patented Oct. 15, 1963

196,627

KICKSTAND

Donald A. Wolf, Covina, Calif., assignor to The Huffman Manufacturing Company, Dayton, Ohio, a corporation of Ohio

Filed June 11, 1962, Ser. No. 70,504

Term of patent 14 years

(Cl. D90—18)

FIG. 1 is a perspective view of a kickstand showing my new design;

FIG. 2 is an elevational view of the side opposite that shown in FIG. 1;

FIG. 3 is a rear elevational view thereof; and

FIG. 4 is a top plan view thereof.

The portions shown in broken lines in FIG. 2 are included for illustrative purposes only.

I claim:

The ornamental design for a kickstand, substantially as shown and described.
